The ornamental design for a handheld lawn mower, as shown and described.

DESCRIPTION

FIG. 1 is a top, front, left side perspective view of a handheld lawn mower showing my new design;

FIG. 2 is a bottom, rear, right side perspective view thereof;

FIG. 3 is a front elevational view thereof;

FIG. 4 is a rear elevational view thereof;

FIG. 5 is a left side elevational view thereof;

FIG. 6 is a right side elevational view thereof;

FIG. 7 is a top plan view thereof;

FIG. 8 is a bottom plan view thereof;

FIG. 9 is an enlarged view of portion 9 shown in FIG. 1;

FIG. 10 is an enlarged view of portion 10 shown in FIG. 1;

FIG. 11 is an enlarged view of portion 11 shown in FIG. 2; and,

FIG. 12 is an enlarged view of portion 12 shown in FIG. 2. The dash-dash broken lines in the drawings depict portions of the handheld lawn mower that form no part of the claimed design. The dot-dash-dot broken lines in FIGS. 1-2 and 9-12 render indication circles and form no part of the claimed design.
